UNITED STATES PATENT OFFICE.

THOMAS SPENCER MILLER, OF SOUTH ORANGE, NEW JERSEY.

EXCAVATING-BUCKET.

1,244,117.

Specification of Letters Patent.

Patented Oct. 23, 1917.

Application filed December 3, 1912. Serial No. 734,673.

To all whom it may concern:

Be it known that I, THOMAS SPENCER MILLER, a citizen of the United States, residing at South Orange, in the county of 5 Essex and State of New Jersey, have invented certain new and useful Improvements in Excavating-Buckets, of which the following is a specification.

My invention relates to new and useful 10 improvements in excavating buckets, and more particularly of that character or type consisting of an open-ended body or shell adapted to be dragged into or through the material to be excavated to fill the bucket 15 through the open end thereof, the bucket body being supported by a bail, or its equivalent, connected to the bucket to one side of its center of gravity, and means being provided for supporting the bucket in 20 carrying position so that it may be carried to a point of discharge, and for tilting it, or permitting it to tilt or gravitate to dump the load.

The invention consists in the improvements to be more fully described hereinafter 25 and the novelty of which will be particularly pointed out and distinctly claimed.

I have fully and clearly illustrated my invention in the accompanying drawings 30 to be taken as a part of this specification and wherein:

Figure 1 is a perspective view of a bucket constructed according to my invention in load-carrying position and showing the rope 35 leads for operating the same.

Fig. 2 is a view in side elevation partly in section of the bucket shown in Fig. 1.

Fig. 3 is a view in front elevation of the bucket shown in Figs. 1 and 2.

Fig. 4 is an enlarged detail view in side elevation partly in section of means for locking the bail to the bucket to maintain the latter horizontal when carrying the load to the point of discharge.

Fig. 5 is an enlarged view in rear elevation partly in section of the bail locking means of Fig. 4.

Referring to the drawings by characters of reference, A designates a bucket body 50 consisting of vertical, parallel side walls 1, a bottom 2, and a rear wall 3, the forward end of the bucket being left open, as shown, and the side walls projecting, as at 4, beyond and forward of the front edge 5 of the 55 bottom, the said edge 5 serving as a cutting or digging edge when the bucket is pulled

into, or through the material being excavated. The forward edge 5 may be provided with digging fingers 6, as shown in Fig. 1 of the drawings, and the bottom may be provided with shoes 7 to give the bucket the proper tilt to cause the forward end thereof to dig into the material. At the rear end of the body A, the side walls of the bucket are connected and braced by a bridge piece 65 8, and at their forward ends, said side walls are connected by an arched bridge member 9 to brace and stiffen the same, and to serve as a support for parts to be presently described. The forward upper ends of the 70 side walls are provided with apertures 10 in which are secured the ends of the members 11 of a split connection, the opposite ends of which are brought together and connected, as at 12, with a hauling or digging line 13. Pivoted to the side walls of the bucket on the outside thereof, and in the embodiment shown, in rear of the center of gravity thereof, as at 14, are the side arms 15 of a supporting bail, the upper 80 ends of which side members converge toward each other and are connected by a cross pin 16 consisting preferably of a bolt, with a pivoted connection 17, to which is connected one end of a hoisting rope or 85 line 18.

The above briefly describes a well-known form of drag bucket operated by a drag or hauling line, to drag the open end of the bucket through or into the material to be excavated in order to fill the bucket, and then be lifted and transferred by a hoisting line to a point where the load is to be discharged. In order that the load may be properly carried to the point of discharge, 95 it is essential that provision be made to maintain the bucket with its bottom in carrying position during the transfer of the load so that the load will be retained in the bucket, and then for permitting the forward 100 end of the bucket to be tilted or to gravitate, under its own weight and the weight of the load to discharge the latter. The improved means I am about to describe relates to a means for maintaining the bucket 105 in carrying position for the purpose just set forth, and consists of a latch or locking device for detachably locking the bail to the forward end of the bucket so that, when the bucket is carried to the point of discharge, the bucket is locked to the bail, whereby the bucket is maintained in car-

rying position, which locking means is adapted to be released upon reaching the point of dump to release the bucket from the bail to thereby discharge the load. I 5 will now proceed to describe the locking means which constitutes an important part of my invention. Mounted upon the arch member 9, connecting the forward ends of the sides of the bucket, are a pair of vertically-disposed parallel plates or brackets 19 carrying at their upper rear ends, or the ends toward the bail, a part in the form preferably of a cross pin 20 bridging the space between said plates or brackets. 10 These plates 19 may be of any suitable construction for accomplishing the purpose for which they are intended, but preferably consist of castings having vertical members 21 and lateral attaching flanges 22 connected 15 and braced by suitable webs 23, which flanges 22 are riveted or otherwise secured to the member 9.

Pivoted, on the outer ends preferably, of the cross pin 16 are the upper ends of two 20 plates 24, 24 constituting the body of a latch to coöperate with the pin 20 to lock the bail to the forward end of the bucket. These plates are maintained in spaced relation by suitable bolts 25 which may carry 25 spacing sleeves 26 if desired. The side plates of the members 24 constituting the latch are formed at their lower rear ends with a locking hook 27, a filler block 28 being interposed between the plates to form a 30 substantial and rigid hook bill, said block being secured in place by rivets 29, 29 let through the side plates 24 and said block. The distance from the pivot 16 of the latch to the receiving hook thereof is such that, 35 when the hook is locked over and receives the pin 20, the lifting of the bucket by the hoisting line 18 will maintain the bucket in proper carrying position to sustain the load therein. At their lower forward ends in 40 advance of the bucket, the plates 24 constituting the latch member, are provided with curved faces 30 which are of such shape and so located that, when the bail is thrown forward, as hereinafter described, preliminary to engaging the latch with the pin, 45 said faces 30 will strike the pin 20 at a point not too near the extreme outer edge of the faces 30 so that said faces will slide or ride upon the pin so that the latch hook 50 passes freely over the pin. These faces 30 are so shaped that they will slide upon the upper surface of the member 9 when they come into contact with the same, and the bill of the hook will not overreach the outer 55 edge of the part 9 before the bail strikes the pin 20. On the under face above the receiver space of the hook 27, the latch member is provided with a stop member 31, which may be integral with the filler block 60 28, said member 31 having a rearwardly-

projecting stop finger 32 to engage and co-operate with the bail, said member 31 also having a lower guide surface 33. The rear end of the finger 32 is so located as to engage the bail 15 when the latter is disengaged from the pin 20 so that the surface 30 will strike the pin 20 at the proper point to ride over said pin when the bail swings over toward the open end of the bucket. This stop 32 is so located that the latch will 75 assume such a position that the recess of the hook will engage the pin 20 when the bail is raised from its lowermost position when pull is exerted on the hoisting line 18 to lift the load. The abutting surface of 80 the stop 32 is located high enough to insure the stop 32 clearing the pin 20 when the bail is raised from its lowest position by pull on the hoisting rope 18.

The surface 33 is made on a gradual curve 85 upward and rearward, and is of such shape and position as to freely ride on the pin 20, and prevent the surface 30 from coming in contact with the upper surface of the member 9, except at a point near the forward 90 end or edge of said surface 9. This is important because, were the latch member permitted to strike down with direct impact upon the member 9, there would be the likelihood of deranging the parts of the latch, 95 bending the pivot pin, and otherwise injuring the latch. By use of the surface 33 to coöperate with the pin 20, the surface 30 will always strike the member 9 adjacent the forward edge thereof with a glancing 100 blow, so that the parts are not injured by the impact. The latch above described is shown in locking engagement with the pin 20 in Figs. 1, 2, 3 and 4, which is the relative position of the parts when the load is 105 being lifted and transferred.

I will now describe the means employed for releasing the latch to permit relative movement between the bucket and the bail, as when it is desired to permit the bucket to drop to discharge its load. This means consists preferably of a releasing dog pivoted on the latch to coöperate with the pin to lift the hook out of engagement therewith. The releasing dog is shown at 115 34 mounted on a pivot pin 35 extending through the plates 24 and bridging the space between the same, said dog being provided with an arm 36 which is connected by a contractile spring 37 with the body of the latch adjacent the pivot pin 16. This dog is arranged to swing in a vertical plane toward and away from the bail. Movement of the dog away from the bail is limited by a suitable stop which may consist of an 120 abutment 38 integral with the block 28, heretofore described. Movement of the dog toward the bail is limited by a suitable stop as 31^a. The dog is so arranged as to rest upon the abutment 38 when the bail is 130

locked to pin 20 (see Figs. 2 and 4). The arrangement and construction is such that, when the hook is engaged with the pin 20 to lock the bail to the bucket, the dog 34 is located between the pin 20 and said stop 38 whereby a pull toward the open end of the bucket on the arm 36 will move the dog 34 on the pin 20 to lift the latch out of engagement with said pin to permit the forward end of the bucket to gravitate.

The operation of the bucket as above described is as follows: The bucket is lowered by paying out the hoisting rope 18 until the bucket rests on or adjacent to the material to be excavated and the bail rocks forward toward the open end of the bucket. If the bucket should engage the material to be excavated at such an angle that the bail will not automatically move toward the front of the bucket, it may be pulled forward by a line 39 extending to a point convenient to an operator. When the bail moves forward the latch will rest with the stop 32 against the bail until the curved face 30 engages the pin 20, thereby causing the latch to lift up and drop down toward the plate 9 as the bail moves forward. During this movement the engagement of the surface 33 with the pin 20 insures the glancing engagement of said surface 30 with the part 9, as heretofore described, and the lower end of the latch passes between the members 19. Pull is then exerted on the drag line 13 to pull the bucket through or into the material to be excavated, so that the bucket is filled with said material, and, during the filling the line 39 is maintained taut so as to hold the bail and the latch in the position just described. When the bucket is filled, pull is exerted on the hoisting line to take up the load, which pull will first operate to lift the bail, the surface 30 riding on the part 9 until the surface 33 engages the pin 20 and further riding thereon until the hook 27 engages the pin 20 to couple the bucket to the bail. The load is then lifted and transferred to the point of discharge, the parts being in substantially the position shown in Figs. 1, 2, 3, and 4. Upon reaching the point of discharge, the latch line 40 is pulled to throw the dog into positive engagement with the pin 20 to lift the latch hook out of engagement with the said pin and permit the forward or open end of the bucket to gravitate.

It will be understood that the latch is so constructed and proportioned and the preponderance of its weight so located that in the extreme angle assumed by the bucket in practical operations the latch will tend to gravitate at all times, so that it will assume such a position as to insure the hook engaging the pin 20 when the bail is lifted. For the purposes stated the forward end of the latch may carry a weight 46.

By pivoting the latch on the pin 16, to which the hoisting line is also connected, I am enabled to distribute the load upon the latch and the bail so that the latter is not subjected to strains tending to bend or break it, and by proportioning the lengths of the latch and bail substantially as illustrated the pull on the bail is at all times substantially lengthwise thereof.

What I claim and desire to secure by Letters Patent of the United States is:—

1. An excavating bucket having an open forward end, a forwardly swinging bail pivoted to the bucket, a latch member pivoted to the bail and having a downwardly directed hook, a part on the forward end of the bucket adapted to be engaged by said hook, and means carried by the latch member and co-operating with said part for disengaging the hook therefrom.

2. An excavating bucket having an open forward end, a bail pivoted to the bucket behind the center of gravity thereof, a pin at the upper end of the bail, a hoisting line connection connected to said pin, a latch member pivoted on said pin, and adapted to engage a part on the bucket, and means carried by the latch and adapted to co-operate with the bucket to disengage the latch.

3. An excavating bucket having an open forward end, a bail pivoted to the bucket behind the center of gravity thereof, a latch member pivoted to the bail and having a downwardly-directed hook, a part on the bucket adapted to be engaged by said hook, and a pivoted dog carried by the latch and adapted to engage said part adjacent the hook to lift the hook out of engagement with said part, a pull line for moving said dog into engagement with said part to disengage the hook therefrom, and a spring for returning the dog to normal position.

4. An excavating bucket having an open forward end, a bail pivoted to the bucket, a latch member pivoted to the bail and having a downwardly-directed hook, a part on the bucket adapted to be engaged by said hook, a stop on the latch, a dog, a spring for moving the dog into engagement with the stop, said dog being arranged to rest on said part when the hook engages said part, and means for swinging said dog to exert its force on said part to disengage the hook from said part.

5. An excavating bucket having an open forward end, a bridge piece, a bail pivoted to the bucket and carrying a latch hook, a part on the bridge piece to be engaged by the latch hook, and a cam surface on the latch to engage said part to cause the hook to strike the bridge piece a glancing blow.

6. An excavating bucket having an open forward end, a bridge piece, a bail pivoted to the bucket and carrying a latch hook

adapted to engage a part on said bridge piece, said latch hook having a curved surface to coöperate with said part to lift the hook over said part when the bail is moved 5 toward the open end of the bucket, and means coöperating with the bail and said part to cause the hook to strike the bridge piece a glancing blow.

7. An excavating bucket having an open 10 forward end, a bridge piece, a bail pivoted to the bucket and carrying a latch hook, a part on the bucket adapted to be engaged by said hook, said latch hook having a curved surface in rear of the hook opening 15 to coöperate with said part to lift the hook over said part when the bail is moved toward the open end of the bucket, and a cam surface carried by the latch piece to cause said first-named surface to strike the bridge 20 piece a glancing blow.

8. An excavating bucket having a forward open end, a bridge piece at the forward end of the bucket, a bail pivoted to the bucket, a latch piece pivoted to the bail, a part on 25 said bridge piece to be engaged by the latch piece, said latch piece having a forward engaging face to ride over said part, and an engaging face in rear of the hook to engage said part to lift the latch piece.

30 9. An excavating bucket having an open

forward end, a bail pivoted to the bucket behind the center of gravity thereof, a pin at the upper end of the bail, a hoisting line connection connected to the pin, and thereby supporting the bucket, a latch pivoted at 35 one end on the said pin and having at its opposite end a hook adapted to engage a part carried by the forward portion of the bucket, and means for releasing said hook from said part.

10. An excavating bucket having an open forward end, a bail pivoted to the bucket behind the center of gravity thereof, a hoisting line connection engaging the upper end 40 of the bail, a latch pivoted at one end on the bail adjacent to said hoisting line connection and having at its opposite end a hook adapted to engage a part carried by the forward portion of the bucket, means on the latch for engaging said part and guiding 45 the hook as the bail swings in either direction, and means for releasing said hook from said part.

In testimony whereof I have hereunto signed my name in the presence of two sub- 50 scribing witnesses.

THOMAS SPENCER MILLER.
